UNITED STATES PATENT OFFICE.

JOHN SCHROEDER, OF DAVENPORT, IOWA.

MOTOR.

1,275,767.

Specification of Letters Patent. Patented Aug. 13, 1918.

Application filed April 30, 1917. Serial No. 165,433.

To all whom it may concern:

Be it known that I, JOHN SCHROEDER, a citizen of the United States, and a resident of Davenport, in the county of Scott and State of Iowa, have invented a new and Improved Motor, of which the following is a full, clear, and exact description.

This invention is an improvement over the construction disclosed in my Patent No. 908,890, and it has reference more particularly to the improved control of the motive fluid.

An object of the invention is to provide a simple, inexpensive and efficient motive-fluid control for a reciprocating engine of a character such as to eliminate motion-transmission means and the flywheel used in connection with my motor as shown in the patent previously mentioned.

With the above and other objects in view, the nature of which will more fully appear as the description proceeds, the invention consists in the novel construction, combination and arrangement of parts as herein fully described, illustrated and claimed.

In the accompanying drawings, forming part of the application, similar characters of reference indicate corresponding parts in all the views.

Figure 1 is a side elevation of my motor, certain parts of which are broken out to show the details of construction;

Fig. 2 is a plan view;

Fig. 3 is a vertical section on line 3—3, Fig. 1;

Fig. 4 is a perspective view of the detachable valve stem for the admission and exhaust valve;

Fig. 5 is a perspective view of the admission and exhaust valve; and

Fig. 6 is a vertical section on line 6—6, Fig. 1, illustrating the control of the inlet and outlet valve.

Referring to the drawings, 7 is the base or bed of the motor at the narrower end of which a lug 8 is provided and to which one end of a cylinder 9 is pivotally secured; for which purpose the cylinder is provided with a bracket or lug 10 engaging the lug 8. Through the other end of the cylinder the piston rod 11 projects. The end of the rod is secured to a crosshead 12 which is guided in the bed and frame 13 secured to the bed 7. A dented surface 14 is provided in the crosshead to form a rack which meshes with a pinion 15 bearing in the bed and frame 13.

An admission and exhaust valve 16 is connected to the ends of the cylinder 9 by conduits 17. The valve proper 16' is so formed that when one of the conduits is in communication with an inlet 18 the other one is in communication with an exhaust or outlet conduit 19. The valve 16' has a prismatic projection 20 at one end thereof which enters a groove 21 of the valve stem 22, which is retained in the casing and in engagement with the valve by a cap 23 detachable from the valve casing and carrying suitable packings 24 for sealing the joint between the cup stem and valve casing. The projecting end 70 of the stem is secured to an arm 25 to oscillate therewith. The arm 25 has a slot 26 engaged by a screw or bolt 27 which is, in turn, secured to the piston rod 28 of a piston 28' mounted to reciprocate in a secondary cylinder 29.

An admission and exhaust valve 30 controls the flow to the ends of the cylinder 29 through passages 31. The valve 30 is connected to the inlet 18 by a conduit 32. A conduit 33 connects the outlet of the valve 30 to the outlet conduit 19. The valve 30 is retained in its casing by a cap 34. To prevent leakage along the stem 35 of the valve 30 the stem is provided with a collar 36 having a beveled surface 37 which sits on a similar beveled surface 38 provided in the valve casing and against which the beveled surface 37 is maintained by the cap 34.

The projecting end of the stem 35 is provided with an arm 39 constrained to oscillate with the valve. The arm carries a swivel block 40 through which a rod 41 is mounted to slide, the end of the rod being connected to an extension 42 from the crosshead. Adjustable collars 43 are provided on the rod 41 on each side of the block 40 whereby the arm 39 is operated when the rod travels through the block.

The valve 30 is operable near the end of each stroke of the main piston 9' through the medium of the rod 41. As shown in Figs. 1 and 2 it has just been operated at the end of the upward movement of the main piston whereby the valve 30 has 100 brought into communication the part above the piston 28' with the exhaust conduit 33, and that below the piston 28' with the conduit 32; in consequence the motive fluid from the inlet conduit 18 has forced the 105 piston 28' up, carrying therewith the arm 25 which oscillated the valve 16' whereby

the end of the cylinder 9 near to the cross-head has been brought into communication with the outlet conduit 19, while the other end of the cylinder 9 has been brought into communication with the motive-fluid inlet conduit 18. This inflow of motive fluid to that end of the cylinder 9 forces the piston outward.

As the piston 9' begins to approach the end of its outward stroke, the collar 43 near the end of the rod 41 engages the arm 39 of the valve 30 and oscillates the valve 30, whereby the part of the cylinder 29 below the piston 28' is brought into communication with the exhaust conduit 33, while the upper part of cylinder 29 is brought into communication with the conduit 32 where-through the fluid enters, the fluid in the part of the cylinder 29 below the piston flowing out through the outlet conduit 33, while the motive fluid entering into the upper part forces the piston valve downwardly carrying therewith the arm 25 which oscillates the valve 16'. This changes the connection of the conduits 17 with the inlet and outlet conduits 18 and 19 respectively. The movement of the piston 9' is thereby reversed and it starts on the inward stroke. This displacement of the piston imparts an oscillatory movement to the shaft 44 to which the pinion 15 is connected.

I claim:

1. A motor comprising a cylinder, a piston in the cylinder, a piston rod, a cross-head for the rod, a valve for controlling the admission and exhaust of the motive fluid to both ends of the cylinder, an arm connected to move with the valve, a piston connected to the arm, a cylinder for the piston, a valve for controlling the inlet and exhaust of the live motive fluid to the ends of the second cylinder, an arm for said valve, and means for actuating said arm from the crosshead.

2. A motor comprising a cylinder, a piston in the cylinder, a piston rod, a crosshead for the rod, a valve controlling the admission and exhaust of motive fluid to the ends of the cylinder, an arm constrained to move with the valve, a second cylinder, a piston therein having a rod projecting out of the cylinder to engage the arm of the valve, said arm having a slot, means in said slot engaging said piston rod of the second cylinder, a valve controlling the admission and exhaust of motive fluid to the ends of said second cylinder, an arm connected to move with the last-mentioned valve, and means for operating said arm from the crosshead near the end of stroke of the first-mentioned piston.

JOHN SCHROEDER.
